EXTENDIBLE ERASER

Jesse J. Robbins, Glendale, Calif., assignor to
Stylofede Corporation, Glendale, Calif., a corporation of California

Application November 10, 1945, Serial No. 627,828

4 Claims, (Cl. 120—38)

1

My invention relates to erasers and more particularly to that class of erasers adapted for attachment to automatic pencils.

Heretofore erasers attached to automatic pencils either extend normally from the end of the pencil opposite the point or are enclosed within the said pencil. In the one case the eraser is exposed to dirt, wear, and the like when not in use; and in the other case it is necessary to remove the cap from the pencil before the eraser may be used, causing inconvenience and possible misplacing of the said cap. Another inconvenience of the conventional type eraser attachment lies in the fact that when the eraser is new, its use in erasing subjects the rubber to extreme bending moments due to the distance between eraser tip and eraser support. Frequently, this occasions breaking of the eraser.

It is my object to provide an eraser attachable to an automatic pencil which is adapted to extend from the end of the said pencil opposite the pencil point and which may be withdrawn or extended from said pencil at the user's wish.

Another object of my invention is to provide support for the said eraser midway between the eraser tip and the eraser support in such manner that when the eraser is new, the bending moment upon the eraser when used is no more than the bending moment would be if the eraser were old and worn down.

A further object of my invention is to provide an extendable eraser construction of the character described wherein the eraser may be conveniently fed from an end of a pencil as it is worn away in use, and wherein a new eraser may be quickly and easily inserted when desired.

Another object of my invention is to provide my extendable eraser attachment of simple, compact construction of a minimum of parts.

Other objects and advantages of this invention, it is believed, will be apparent from the following detailed description thereof as illustrated in the accompanying drawings.

In the drawings:

Figure 1 shows a side view of an automatic pencil having my extendible eraser extending therefrom.

Figure 2 shows a longitudinal cross section of a portion of the eraser containing pencil, taken along the line 2—2 of Figure 1.

Figure 3 shows a longitudinal cross section, taken substantially along the line 3—3 of Figure 2, but with portions of the interior mechanism shown in elevation.

2

Figure 4 shows a cross section of my invention taken on the line 4—4 of Figure 2.

Figure 5 shows a cross section of my invention taken on the line 5—5 of Figure 3.

5 Figure 6 is a perspective view of a screw element forming part of the present construction.

Figure 7 shows in perspective the eraser rubber and supporting member.

10 The extendible eraser construction of the present invention consists, briefly, in the combination with a tubular pencil body 10 having a bore 11 opening to an outer end 12 thereof, of a hollow nut 18 journaled for rotation at the body end 12 and having an internally threaded opening 19 aligned with the bore 11; a tubular cap member 28 secured to the nut 18 for rotation therewith and having a bore 29 through the length of the cap member aligned with the bore 11 and opening 19; a screw element 38 threadably engaged

20 with the nut 18 and mounted for longitudinal reciprocation in the aligned bores 11 and 29 of the body and cap; means 42 in the bore 11 in

25 slidable engagement with the inner extremity of the screw element 38 for restraining the latter against rotation relative to the body; and an eraser 32 mounted for reciprocation in the cap bore 29 for extension from the outer open end 30 thereof and detachably secured to the screw element 38 for longitudinal displacement thereby

30 upon rotation of the nut 18 and the cap 28.

Any suitable means may be used for rotatably supporting the nut 18 at the outer end 12. As

here shown, the end 12 of the body is of reduced diameter and externally threaded for receipt of a

surrounding, internally threaded collar or ferrule 14 which likewise surrounds the periphery of a

shoulder 22 on the nut 18. As will be noted from

Figures 2 and 3, the outside diameter 20 of the nut shoulder is the same as the diameter of the

reduced end 12 of the body, and the inner face

35 of the nut directly abuts and is slidably upon the

end face of the body and is so retained in this

position by the surrounding ferrule, the latter

having an internally extending annular shoulder

40 16 at its end which engages the exterior side of

shoulder 22. The body of the nut extends from

the end of the ferrule and slidably receives the

45 adjacent end of the cap 28, the internal diameter

of the cap at such end being substantially equal

50 to the outside diameter 24 of the nut body there-

at, so as to provide a tight fit joining the cap

and the nut for common rotation. In this man-

55 ner, the nut 18 is journaled by the ferrule 14 for

free rotation of the nut relative to the pencil body

10, and the tight fit of the cap 28 upon the nut

affords a convenient means of rotation of the nut.

The screw element 38 is here of U-shaped construction, having elongated, substantially parallel legs 39 and 41 which are joined in a flat connecting end 43. A plurality of teeth 40 are provided on the legs 39 and 41 for threadable engagement in the internal spiral thread 26 in the nut opening 19, the teeth 40 being provided over substantially the full length of the legs 39 and 41. In this manner the screw element is threadably engaged in the nut 18 medially of the length of the element, with its opposite ends extending into the aligned body and cap bores 11 and 29. As hereinabove noted, means 42 is provided in the bore 11 for restraining the screw element against relative rotation with respect to the body 10, so that upon appropriate rotation of the nut 18 the screw element will be displaced longitudinally of the bores 11 and 29. This means 42 may be of any convenient form and as here shown consists of a U-shaped member having flat, elongated parallel legs 43 and 45 fixed at their free inner ends to a transverse wall 44 provided by the body 10 across the interior of the bore 11 and extending into the space between the legs 39 and 41 of the screw member to restrain the latter against rotation relative to the body 10.

The length of the screw element 38 and more specifically the toothed legs 39 and 41 thereof is such as to permit the extension of the end 43 of the element outwardly through the cap bore 29 to the exterior of the cap outside of the cap opening 30. Preferably, some suitable means is provided for limiting the outward extension of the screw element and in the present instance such means is afforded by lugs 46 which are struck out from the legs 39 and 41 adjacent their inner ends and which on outward extension of the screw will abut the inside face of the nut to prevent further extension of the screw member.

The eraser 32 may be of conventional cylindrical form, of suitable rubber material for erasing purposes, having an external diameter enabling it to fit within and be displaceable through the cap bore 29. Preferably, the latter is tapered toward the end 30 so that the bore aperture thereat tightly embraces the periphery of the eraser 32 so as to firmly support the eraser body at this point. The opposite end of the eraser is desirably embraced within a surrounding sheet metal housing support 34, which, in accordance with the present invention, is provided with a pair of longitudinally extending clip or bracket elements 36 of hook shape which are engageable over the opposite sides of the flat end 43 of the screw element. The eraser may be most conveniently secured to the end 43 of the screw element by displacing the latter exteriorly of the cap opening 30 and then sliding the clip elements 36 transversely onto the opposite edges of the end 43, it being noted that the end is somewhat broader than the legs 39 and 41 so as to leave the opposite edges of the end 43 free for receipt of the clips 36. When the eraser support is thus centrally mounted on the end 43, the latter may be retracted into the bore 29 of the cap, which confines the eraser support against release laterally from the end 43.

The U-shaped construction of the screw element 38 affords a resilient spacing of the opposed legs 39 and 41 enabling the springing of these legs toward each other for insertion in the nut 18. Advantage may also be taken of this resilient construction in effecting disassembly of the mechanism for repair or replacement of the parts,

including the replacement of the eraser 32. In such case, the ferrule 14 may be unscrewed from the pencil body so as to remove the associated nut 18, cap 28, screw element 38 and eraser 32. The inner extremities of the legs 39 and 41 may be pinched together, releasing the teeth 40 from the nut thread 26, when the screw element and attached eraser may be pushed through the nut opening and the bore 29 of the cap. If desired, the cap 28 may also be forcibly slid from its embraced position on the screw.

I claim:

1. A device of the class described comprising: a housing having a bore opening to an end thereof; a ferrule threaded on said housing end; an internally threaded nut rotatably carried by said ferrule in alignment with said bore; a tubular cap tightly fitted at one end on said threaded nut to rotate therewith in alignment with said bore and having an open opposite end; an eraser rubber mounted within said cap and extendible through said outer open end thereof; a U-shaped screw-member carrying said eraser rubber and having spaced substantially parallel legs formed with teeth threadably engaged with said threaded nut to extend or withdraw said eraser rubber through said open cap end; and a member mounted within said housing and positioned between said legs to prevent the rotation of said screw member with respect to said housing.

2. An eraser supporting and displacing mechanism comprising, a casing having a bore opening to an end thereof, a nut member having an internally threaded opening and being journalled for rotation relative to said casing with said opening aligned with said bore, a tubular cap detachably secured to said member for rotation therewith and having an interior bore aligned with said casing bore and member opening, a U-shaped screw member having a pair of spaced substantially parallel legs formed with teeth threadably engaged in said first member opening for longitudinal reciprocation in said bores, guide means provided in said casing bore engageable with said legs and restraining said screw member against rotation relative to said casing, the opposite end of said screw member being positioned in said cap bore, and an eraser mounted for reciprocation in said cap bore and detachably secured to said last-named end of said screw member.

3. An eraser supporting and displacing mechanism comprising, a casing having a bore opening to an end thereof, tubular means secured to said casing and journalled for relative rotation thereto and having an internal bore aligned with said casing bore, a U-shaped member having a pair of spaced substantially parallel legs and a connecting side mounted within said bores for longitudinal reciprocation of said member therein, thread means connecting said member and said first means for effecting said reciprocation upon rotation of said first means, guide means in said casing bore engageable with said legs and restraining said member against rotation relative to said casing, an eraser mounted for reciprocation in said bore in said means, and means detachably securing said eraser to said member side.

4. An eraser supporting and displacing mechanism comprising, a casing having a bore opening to an end thereof, tubular means journalled for rotation in said housing and having an internal bore aligned with said first bore, a screw element threadably engaged medially of its

length in said means bore, means restraining said screw element against rotation relative to said casing thereby causing longitudinal reciprocation of said element upon rotation of said first means, one end of said element extending into said bore of said first means and being formed with a flat side positioned in a plane across said bore substantially perpendicular to the longitudinal axis thereof, an eraser mounted for reciprocation in said bore of said means, and a mounting member secured to said eraser and formed with a pair of end-wise extending clip elements engageable with said flat side of said element.
